UNITED STATES PATENT OFFICE.

WILLIAM F. AMBACK AND LEONARD C. HOLLINGWORTH, OF PROVIDENCE,
RHODE ISLAND.

REST FOR CLOTH-SHEARING MACHINES.

SPECIFICATION forming part of Letters Patent No. 634,603, dated October 10, 1899.

Application filed February 9, 1899. Serial No. 705,088. (No model.)

To all whom it may concern:

Be it known that we, WILLIAM F. AMBACK and LEONARD C. HOLLINGWORTH, of Providence, in the county of Providence and State 5 of Rhode Island, have invented a new and useful Improvement in Rests for Cloth-Shearing Machines; and we hereby declare that the following is a full, clear, and exact description of the same, reference being had to the 10 accompanying drawings, forming part of this specification.

This invention has reference to an improvement in the mechanism by which the ends of the cloth-rest are automatically adjusted to 15 the width of the cloth, so that the whole width of the cloth is exposed to the cutter, while the selvage of the cloth is kept from contact with the cutters.

As heretofore constructed the cloth was 20 guided onto the feelers operating the adjustable rest and held against the same by arms or rollers and the serrated edges of the feelers moved in the same segmental path below the normal line of the cloth. As the condition 25 of the selvage differs in different weaves, some selvage being more slack than others, the feelers as heretofore constructed did not control the rest as promptly as is desired to 30 secure the shearing of the cloth uniformly up to and along the edge of the selvage.

One object of this invention is to dispense 35 with the arms or rollers for holding the cloth to the feelers and secure a clear view of the cloth as it passes over the rest.

Another object of the invention is to adjust 40 the feelers to the varying condition of the selvage.

The invention consists in the peculiar and 45 novel construction whereby the feelers may be adjusted to the cloth and the selvage and to move in a path beyond the normal path of the stretched cloth.

Figure 1 is a front view of the automatically-adjustable cloth-rest, showing the same 50 with the cover removed. Fig. 2 is a transverse sectional view of the same, showing the feelers adapted to swing above the normal line of the cloth and the selvage. Fig. 3 is a side view of the cam-plate, showing the serrated feeler-plates coöperating with the same. Fig. 4 is a side view of the cam-plate and the

serrated feeler-plates as viewed from the side opposite to the view of Fig. 3. Fig. 5 is a sectional view of the cam-plate and the adjustable feelers coöperating with the same. 55

In the drawings, A indicates the sliding sections of the cloth-rest controlled by the slide B. The bracket C is adjustably secured to the slide B. A ratchet-bar D, provided with ratchet-teeth on each edge, is placed in 60 ways on each end of the rest, and these ratchet-bars are connected with mechanism by which they are continuously reciprocated. The cam-disk E is pivotally supported on the bracket C, so that the cams may engage with 65 the ratchets on the opposite sides of the ratchet-bar D. The casing F incloses the mechanism and forms the support of the cloth. The broken line f indicates the line of the cloth as it passes to the cloth-rest. 70

So far as above described the cloth-rest is in construction and operation the same as the cloth-rest shown and described in United States Patent No. 598,264, of February 1, 1898, to Leonard C. Hollingworth, with the arms 75 by which the cloth is held against the feelers omitted.

In our present invention the feelers are adjustably secured to the cam-plate E and extend beyond the line on which the stretched 80 cloth passes to the cloth-rest. The serrated feeler E' is provided with a slot, and a clamp-screw extending through the slot secures the feeler to the plate E', so that it may be adjusted to engage with the body of the cloth. 85 The serrated feeler G is adjustably secured to the cam-disk E and is provided with the segmental convex shield G', so that the selvage is guided onto the serrated feeler G and prevented from entering the space between 90 the two feelers.

By the use of the extended feelers the serrations of the feelers are brought in contact with the stretched cloth as it passes to the rest without the use of the rollers or arms extending across the front of the cloth and without deflecting the cloth, the view of the cloth is unobstructed, and the cloth may be more readily placed on the machine. 95

By the use of the independently-adjustable 100 feelers the serrated edges of the feelers can be adjusted to the condition of the selvage,

the feeler G being projected beyond the feeler E' for loosely-woven selvage, so as to maintain the desired contact with the selvage, and the cloth-rest may be adapted to secure the best results with cloth having tight or slack selvage.

Having thus described our invention, we claim as new and desire to secure by Letters Patent—

10 1. In a cloth-rest for cloth-shearing machines, the combination with the reciprocating ratchet-bar and the cam-disk, of two serrated feelers, adjustable toward or from their pivotal support, independent of each other and adapted to swing into the normal path of the cloth as it passes to the rest; whereby the feeler may be adjusted to the cloth and the selvage, as described.

15 2. In a cloth-rest for cloth-shearing machines, the combination with the mechanism

controlling the adjustment of the rest, of two serrated feelers and a shield closing the space between the two feelers; whereby the selvage is guided from one feeler to the other, as described.

25 3. In a cloth-rest, the combination with the reciprocating ratchet-bar D, the bracket C and the cam-disk E, of the feeler G adjustably secured to the cam-plate, the plate E² connected with the cam-plate and the feeler E' adjustably secured to the plate E²; whereby the feeler may be adjusted to the cloth and to the selvage, as described.

In witness whereof we have hereunto set our hands.

WILLIAM F. AMBACK.

LEONARD C. HOLLINGWORTH.
